UNITED STATES PATENT OFFICE.

FRANK H. HINKLEY, OF ERIE, PENNSYLVANIA.

CRANK-CASE HEATER.

Application filed June 23, 1926. Serial No. 118,105.

This invention relates to a device which may be used on motor vehicles in cold weather for heating the oil in the crank case by means of heat derived from the exhaust 5 pipe.

The object of the invention is to provide a device of this character which may be easily installed, which is simple and practical in construction, and which will operate efficiently in heating the oil without in any way obstructing the free circulation thereof.

The specific construction of the invention and the advantages thereof will be more fully explained in the following detailed description, which is to be read in connection with the accompanying drawing illustrating the same in its preferred form.

In the drawing:

Figure 1 is a side elevation of the invention, together with the parts of the motor vehicle to which it is connected.

Figure 2 is a plan view thereof.

Figure 3 is a section taken on the line 3—3 of Figure 2.

Figure 4 is a detail view of the heating element which is to be mounted inside of the crank case.

The invention is illustrated in connection with a crank case 5, and an exhaust pipe 6 leading from the exhaust manifold 7 of a motor vehicle. The heating element 8 is in the form of a flat oblong hollow casing, adapted to be supported within the crank case 5 near the bottom thereof, and formed with threaded openings 9 at opposite ends thereof. One of these openings is adapted to be connected to the threaded end of an inlet conduit 10, and the other to an outlet conduit 11. The other end of the conduit 10 is connected, as at 12, to the exhaust pipe 6, and its intermediate portion includes a valve housing 13 with a valve 14, which is opened or closed by means of a laterally extending arm 15, the latter being actuated by any suitable means, as, for instance, a rod 16, extending to the dash 17 of the motor vehicle. Nuts 18 and gaskets 19 are mounted on the threaded portions 10 and 11 respectively, outside of the crank case 5. After the ends of these conduits have been connected with the threaded openings 9, the

nuts 18 are adjusted toward each other until the gaskets are tightly clamped against the walls of the crank case, so as to form leak-proof connections therewith. 55

The casing 8 is thin enough, so that it will be entirely immersed in the crank case oil, and will not interfere in any manner with the circulation thereof. The casing 8 is also provided at its corners with feet 20, 60 which positively maintain it sufficiently above the bottom of the crank case, so that the oil may circulate underneath the same, and there will be no obstruction to the drainage of the oil from the crank case when the bottom plug 21 is removed. The interior of the casing 8 is free from obstruction, and allows the free passage of the heated gases from the exhaust pipe 6 whenever the valve 14 is opened. The walls of the casing 8 are 70 comparatively thin, so that the heat will be quickly conducted therethrough and into contact with the oil.

It will be understood, of course, that the shape and dimensions of the casing 8 may 75 be considerably modified, and that the various connections and means for operating the valve may also be modified considerably without any material departure from the salient features of the invention as claimed. 80

What is claimed is:

In a motor vehicle, the combination with the crank case and exhaust pipe, of a flat hollow casing normally covered by the oil in the crank case and having feet to positively 85 maintain it in spaced relation to the bottom of the crank case, a conduit affording communication between the exhaust pipe and the interior of said hollow casing and passing through one side wall of the crank 90 case, an outlet conduit extending through the opposite side wall of the crank case and also communicating with the interior of said hollow casing, each of said conduits having an integral end portion which is 95 threaded through the side wall of the crank case and the side of said hollow casing.

In testimony, that I claim the foregoing as my own, I have hereto affixed my signature.

FRANK H. HINKLEY.
